MEANS FOR REDUCING STATIC ELECTRICITY CHARGES IN NONELECTROCONDUCTIVE STYLI

Dallas R. Andrews, Collingswood, N. J., assignor to Radio Corporation of America, a corporation of Delaware

Application June 28, 1947, Serial No. 757,727

7 Claims. (Cl. 274—38)

1

This invention relates to recording devices, and more particularly to a cutting stylus for recording a sound track in a phonograph record.

Phonograph record blanks having lacquer surfaces in which sound grooves may be cut or engraved have been in use for many years. For this purpose, a suitable engraving tool is employed which cuts out of the lacquer surface a thread-like shaving as it forms the sound groove. This shaving has a tendency to curl and frequently winds itself around the cutting tool or stylus, and unless it is removed, it is quite apt to interfere with the recording operation. To accomplish this, there is usually provided a suction line which terminates in proximity to the cutting stylus and draws off the thread as it is formed.

One of the most common materials of which cutter type recording styli are made is sapphire. Since both sapphire and lacquer are non-conductors of electricity, the friction between the front side or cutting face of the sapphire stylus and the lacquer thread as the latter moves upwardly from the disc along the cutting face in the course of the recording operation generates a charge of static electricity on the thread. The charged thread is then so strongly attracted to the neutral disc that the vacuum system frequently is unable to remove the thread satisfactorily.

The primary object of my present invention is to provide an improved recording system in which this difficulty is obviated.

More particularly, it is an object of my present invention to provide an improved recording stylus of sapphire or other suitable, non-conducting material which will reduce or eliminate the accumulation of a charge of static electricity in the thread and/or disc of lacquer or the like during the recording operation.

Another object of my present invention is to provide an improved recording stylus as aforesaid which will help reduce the load on the thread removing suction system of the recording apparatus so as to enable the suction system to remove waste thread without difficulty.

Still another object of my present invention is to provide a method of converting present day, non-electroconductive styli to accomplish the improved results set forth above.

It is also an object of my present invention to provide an improved recording stylus as aforesaid which is simple in construction, hardly more expensive than conventional recording styli known heretofore, and which is highly efficient in use for the intended purpose.

In accordance with my present invention, I

2

provide on the front or cutting face of a sapphire or other similar non-conducting stylus an electroconductive layer which is connected to a suitable ground point, as through the metallic socket 5 and supporting arm in which the stylus is mounted. As the thread is cut in the blank lacquer disc, it rides up somewhat along the front cutting face of the stylus and therefore is in contact with the aforesaid electroconductive layer. Any static electric charge which is created as a result of the friction between the stylus and the lacquer or other similar, non-conductive record blank will leak off along the above-mentioned electroconductive layer. Thus the thread 10 will not acquire a charge which will cause it to be attracted to the disc, and the suction system 15 will be adequately effective to draw it off.

The novel features characteristic of my invention, as well as additional objects and advantages thereof, will be better understood from the following description, when read in connection with the accompanying drawing in which

Figure 1 is a fragmentary, perspective view of a record blank and cutting stylus according to 20 one form of my invention,

Figure 2 is a side elevation of a slightly different form of cutting stylus in accordance with my present invention,

Figure 3 is a front elevation of the stylus shown in Figure 2, and

Figure 4 is a sectional view taken on the line IV—IV of Figure 3.

Referring more particularly to the drawing, there is shown, in Figure 1, a record blank 1 with which a cutting stylus 3 cooperates to form a sound groove 5 as the blank 1 rotates in the direction of the arrow A and the stylus 3 is caused to vibrate in well known manner. The blank 1 may be made of lacquer, Celluloid, Vinylite, wax or any other of the many well known, non-electroconductive materials used heretofore. The stylus 3, which is preferably of sapphire, but may be made of diamond, agate, emerald, hard synthetic resinous material, or any other suitable non-electroconductive material, is formed with a 35 suitably tapered cutting end or point 7 of groove-forming configuration, rearwardly extending clearance surfaces 8, and a front cutting face 9 terminating in a sharp cutting edge for cutting out of the blank 1 a thread 11 as the recording operation proceeds. The groove 5 results from the removal of the record blank material 40 represented by the thread 11.

The characteristics of most suitable record materials, and particularly the lacquers used for record blanks, are such that the thread 11 thereof 45 tends to curl up after first riding up along the

front cutting face 9 of the stylus. Also, as mentioned previously, the friction between the non-conductive, conventional recording styli and the non-conductive record blanks creates a charge of static electricity as a result of which the thread 11 tends particularly to be attracted by and to curl back toward the blank 1, thereby often resulting in failure of the suction device (not shown) usually provided for removing the thread 11 as it forms.

In accordance with my present invention, the stylus 3 is provided on its front cutting surface 9, along the length thereof, with a layer of electroconductive material 13. The layer 13 may be formed by sputtering onto the surface 9 a coating of gold, silver or other, suitable metal, or it may be formed by evaporating chromium or some other, suitable, hard metal onto the surface 9. Where gold is sputtered onto the surface 9, the gold layer 13 may then be plated with some other, hard metal, since gold is rather soft. Instead of sputtering or plating the layer 13 onto the surface 9, a thin strip of suitable metal may be cemented or otherwise wise suitably secured thereto. In any case, the layer 13 will extend up along the front surface 9 of the stylus into engagement with a metallic or other electroconductive socket 15 in which the stylus is securely mounted and which is suitably connected to ground, as through its supporting arm (not shown). Thus, as the thread rides up along the electroconductive surface layer 13, any charge of static electricity which may be generated will leak off and the suction apparatus will have no difficulty in removing the thread 11.

In the stylus of Figures 2-4, which is also of non-conductive material, there is provided a longitudinally extending groove 17 along the front surface 9, an electroconductive filler 19 being seated in the groove 17. The filler 19 may be constituted by a metallic strip or rod which is cemented in place in the groove 17 and is preferably finished off flush with the front surface 9 of the stylus. As in the stylus of Figure 1, the conductive filler 19 has contact with the grounded, conductive socket 15 and it will, therefore, effectively carry off any static charges of electricity generated during the recording operation as the thread 11 rides up therealong.

From the foregoing description, it will be apparent that I have provided an improved recording stylus which has a distinct advantage over similar styli previously known. Moreover, it will be apparent that prior art sapphire and similar styli (which are preferred over metallic styli because they retain their sharp cutting edges much longer) can be converted readily into styli according to my present invention by merely applying to the front cutting surfaces thereof an electroconductive layer as above described. Although I have shown and described but two forms of styli according to my invention, it will, no doubt, be apparent to those skilled in the art that many other forms thereof, as well as changes in those described above, are possible within the spirit of my invention. I therefore desire that the foregoing shall be taken merely as illustrative and not as limiting.

I claim as my invention:

1. A phonograph recording stylus of the type adapted to remove a thread from a record blank in the course of forming a groove therein, said stylus comprising an elongated body of non-electroconductive material having a cutting face and rearwardly extending clearance sur-

faces, said cutting face terminating in a sharp cutting edge having a groove-forming configuration and being engageable by said thread during its formation, and an electroconductive member associated with said cutting face and disposed on said stylus in a position to be engaged by said thread.

2. A phonograph recording stylus of the type adapted to remove a thread from a record blank in the course of forming a groove therein, said stylus comprising an elongated body of non-electroconductive material having a cutting face and rearwardly extending clearance surfaces, said cutting face terminating in a sharp cutting edge having a groove-forming configuration and being engageable by said thread during its formation, and a layer of electroconductive material on said cutting face disposed to be engaged by said thread.

3. A phonograph recording stylus according to claim 2 wherein said layer of electroconductive material comprises a strip of metal adhered to said cutting face along the length thereof.

4. A phonograph recording stylus of the type adapted to remove a thread from a record blank in the course of forming a groove therein, said stylus comprising a cutter of non-electroconductive material having a cutting face engageable by said thread during its formation, said cutter having a longitudinally extending groove therein at said cutting face, and a filler of electroconductive material in said groove.

5. A phonograph recording stylus according to claim 4 wherein said filler is flush with said cutting face.

6. A phonograph recording stylus according to claim 4 wherein said filler is constituted by a metallic strip seated in said groove.

7. In a phonographic recording device, the combination of an electrically grounded stylus holder, and a cutting stylus carried by said holder for cooperation with a record blank to cut a thread therefrom while forming a groove in said blank, said stylus being of non-electroconductive material and having a cutting face engageable by said thread during its formation, and an electroconductive member associated with said cutting face and disposed on said stylus in a position to be engaged by said thread, said member having electrical contact with said holder.
